UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

TRANSOM DRAFT-GEAR.

1,149,220.

Specification of Letters Patent.

Patented Aug. 10, 1915.

Application filed December 3, 1913. Serial No. 804,432.

To all whom it may concern:

Be it known that I, JOHN M. ROHLFING, residing at St. Louis, Missouri, and being a citizen of the United States, have invented certain new and useful Improvements in Transom Draft-Gear, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a plan view of one embodiment of my invention arranged in a cast metal bolster and shows on the left-hand side a horizontal section through the center of the gear on line E—E of Fig. 2, and on the right-hand side a plan view of the bolster showing the hole F through which parts of the gear are inserted, and in dotted lines the parts of the gear which cannot be seen through the hole. Fig. 2 shows on the left-hand side a side elevation of the bolster with the gear in dotted lines and the part of the draft arm at line A—A in section. On the right-hand side of the same figure is shown a vertical section through the center of the gear taken on line B—B of Fig. 1. Fig. 3 is a cross section through the draft gear and bolster taken on line C—C of Fig. 1 and showing the strap G as a method of holding the spring in place. Fig. 4 is a section through one of the two tongues L of the draft arm taken on line D—D of Fig. 1.

This invention relates to the class of gear known as the transom draft gear in which the buffing and pulling stresses to which a draft gear is subjected are applied directly to the transom, or bolster, instead of being transmitted mainly through the center sills to which in ordinary construction the draft sills, with the draft gear, are attached. This, of course, is a great advantage, as by distributing the stresses through more of the longitudinally extending parts there is less chance of displacing or breaking the members. But with such construction there is the disadvantage of throwing the shocks entirely against the side of the bolster at

the center causing a horizontal bending moment for which the ordinary bolster is not designed. With my arrangement this detriment is overcome to a great extent by so designing the gear that a large part of the stress is thrown from the center of the bolster or load-carrying transom, where the draft arm applies it, out toward the ends of the bolster thus absorbing the forces in the longitudinal line of the bolster where it can do no harm. A further advantage is that the gear is a combination spring and friction gear. This is all accomplished by the following arrangement which with reference to the drawings explains the form I have shown for accomplishing these results: In said drawings I indicates the friction elements and J' guiding rollers for same which cause I to travel more freely, as will be hereinafter set forth. The friction blocks I are dropped into the bolster through the openings F and the rollers J' are inserted in the semicircular receiving grooves in the sides of I after which the whole is shoved forward, that is, toward the center of the bolster into the receiving pockets P formed in the sides of the draft arm J which is formed with tongues or arms L which have been slid through the bolster openings K, one entering on each side of the integral center filler or strut M of the bolster, and joined at their rear ends by the member N shown at a casting fitting into recesses N' of the draft arms and secured thereto by bolts, thus affording a limiting stop to the forward movement of the draft arm under pulling strains, as said casting N after the draft arm has traveled forward the required distance will butt against rear or inner face M' of the integral strut M of the bolster. Under buffing the portion O of the draft arm itself will butt against the outer face M² of the strut M. The springs H are then inserted in the hole F and held in place by the strap G, which is bolted to the sides of the bolster. The draft arm J is a movable draft sill, and when it is pulled or pushed by the coupler to which it is attached, the V-shaped portion P pushing against the wedge shaped end of the friction member I will force I back into the pocket in the bolster compressing the springs H and at the same time as the arm J is traveling past I which is held by the bolster it can be readily seen that

the engaging portions of the friction elements I and the draft arm will be in sliding engagement, causing friction.

In applying the pull or push to the forward or wedge shaped end of the friction and spring actuating members I it will be seen that the tendency would be for I to swivel until it bears against the walls of the bolster only on two diagonal corners of I, which would tend to prevent the easy rearward or spring compressing movement of same. The rollers J' obviate this as the two diagonal rollers will be the bearing points during travel of I. It will be seen that the tendency of the gear is to center the coupler, as in case the draft arm J tends to swivel about the center of the bolster, as when the car travels around a curve, it would cause compression of the gear and when the swiveling force is taken away the expansion of the gear would tend to return the draft arm to its normal position.

From the foregoing it will be noted that I have provided in combination a bolster having pocketed middle portions with such pockets extending longitudinally of the bolster at each side of its center, and in said pockets are seated springs and guided plungers, said plungers having relatively frusto-conical contiguous ends, and said plungers are pocketed in recesses or pockets suitably formed for that purpose. The outer ends of the bolsters are preferably rigidly connected to side sills or side plate girders, and the draft transmitting member extending longitudinally is, with relation to the car underframe, a floating member.

What I claim is:

1. In a transom draft gear, a combination comprising a bolster having pockets, an interposed combined center-filler and guide, a draft transmitting member spanning the same, and friction producing elements in said pockets at opposite sides of said draft transmitting member.

2. In a transom draft gear, a bolster having longitudinally extending pockets and an interposed combined center filler and guide.

3. In combination, a bolster having pockets therein on a common center line, yieldingly held friction producing elements in said pockets, a draft transmitting member movable with relation to said bolster

transversely of said pockets, and friction producing elements carried by said draft transmitting member.

4. In combination, a bolster having longitudinally extending pockets therein, a draft transmitting member extending through said bolster, and coöperating longitudinally movable and transversely movable friction producing elements carried respectively in said pockets and by said draft transmitting members, said friction-producing elements being normally maintained in alinement.

5. In a transom draft gear, a combination comprising a pocketed transom or bolster having a central filler intermediate its pockets, compressible means in said pockets and a draft member adapted to cause compression of said compressible means.

6. In a transom draft gear, a combination comprising a pocketed transom or bolster having a central filler intermediate the pockets, compression and friction-producing means in said pockets, and a draft member movable transversely of said pockets and adapted to co-act with said compression and friction-producing means.

7. In combination, a bolster having a central filler and pockets in alinement with said filler, a bifurcated draft transmitting member extending through said bolster across the mouths of said pockets, coöperating friction producing elements carried by said bolster and said draft transmitting member, and a filler guide in the bolster between the bifurcated portions of said draft transmitting member.

8. In combination, a bolster, friction blocks carried in said bolster, a bolster center filler and a draft member spanning said filler and in frictional contact with said blocks.

9. In combination, a bolster or load-carrying transom, friction blocks held in said bolster and extending into passages extending transversely through the bolster, and a draft member in frictional engagement with said friction blocks.

In witness whereof I have hereunto set my hand in the presence of two witnesses.

JOHN M. ROHLFING.
